AUTOMATIC TRAFFIC CONTROL SYSTEM

Samuel C. Roth, Allentown, Pa., assignor to Automatic Signal Corporation, East Norwalk, Conn., a corporation of Delaware

Application February 19, 1936, Serial No. 64,771

1 Claim. (Cl. 177—337)

This invention relates to electrically operated traffic signal lights and has for an object to provide an automatic signal device of the stop and go, or stop, caution, and go type capable of adjusting itself to varying conditions of traffic at all times.

A further object is to provide a device of this character adapted to be installed at intersections where traffic is unequally divided and provide positive safety to vehicles desiring to cross the main highway.

A further object is to provide a device of this character which will so control traffic that the traffic on the main highway will have uninterrupted right of way as long as no vehicles appear on the cross road to contest right of way.

A further object is to provide magnetically operated switches, responsive to cams, or contacts on the program control rotor, and a switch operated by vehicles on the cross road, to operate the traffic signal on the main highway as an ordinary stop and go signal light as long as there are vehicles on the cross road to cross the intersection, and to maintain the traffic signal continuous as a go signal for traffic on the main highway when no vehicles are on the cross road, thus preventing the unnecessary interruption of the main highway traffic by a stop signal when no traffic appears on the cross intersection.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a diagrammatic view of traffic signal apparatus constructed in accordance with the invention and showing the motor circuit open to maintain the green or go light continuously on the main highway.

Figure 2 is a view similar to Figure 1 but showing the motor circuit closed to turn the rotor and the upper magnetically operated switch in open position thus to operate the device as a continuous stop and go signal of the conventional type.

Figure 3 is a view similar to Figure 2 but showing the upper switch of the pair of magnetically operated switches in closed position to permit stopping of the program control rotor by cam 25 when one revolution of the rotor has been completed.

Figure 4 is a diagrammatic view showing how

certain cams on the program control rotor close associated switch contacts.

Figure 5 is a diagrammatic view showing how another cam on the program control rotor closes associated switch contacts.

Figure 6 is a diagrammatic view showing suggested arrangement of the signal apparatus at an intersection of a main highway and a cross road.

Referring now to the drawings in which like characters of reference designate similar parts in the various views, 8 designates a traffic signal of the type adapted to indicate a go or green signal 9 on the main highway simultaneously with a stop or red signal 10 on the intersecting cross road and vice versa. Vehicle operated switches 11 are disposed on the cross road in the path of vehicles approaching the intersection from either direction and these switches are shown as the type adapted to be closed by contact with a vehicle 10 passing thereover although any preferred type of vehicle operated switch may be employed.

Assembled with the traffic signal 8 are a pair of opposed electro-magnets 12 and 13 and between the poles of the magnets there is mounted an armature 14 which is magnetically attracted by one or the other of the magnets to open and close a switch 15 which controls the motor circuit of the traffic signal. The switch 15 may be a single throw switch of the snap type adapted to be yieldably held at either limit of its movement, at one limit of its movement engaging a switch contact 16 in the motor circuit, shown best in Figure 2.

When the vehicle operated switch 11 is closed by a vehicle passing thereover when approaching the intersection, a circuit 17 is closed through the magnet 13 which is thus energized to attract the armature 14 and close the switch 15 in the circuit 18 of the traffic signal motor 19. The motor rotates the program rotor 20 through a worm 21 and worm gear 22 to set in motion the program control cams 23.

The program control cams operate in the usual manner to close switch contacts 24 in the signal light circuits in sequence to first change the signal to caution or amber for the main highway. Then after an interval the signal will be changed to go or green for the cross road and simultaneously to stop or red for the main highway. After another interval the signal will change to caution for the cross road and thereafter to stop or red for the cross road and simultaneously to go or green for the main highway.

The latter or go signal for the main highway

- will remain continuous as long as no other vehicles appear on the cross road at the intersection and this is accomplished by stopping the rotor at the end of one revolution by means of a cam 25
- 5 on the program control rotor. The cam is disposed to affect contact 26 preferably at the end of the predetermined go period for the main highway and closes switch contacts 26 in a circuit 27 which energizes the electro-magnet 12. When 10 the magnet is energized it attracts the armature 14 to open the switch 15 which breaks the motor circuit, as shown in Figure 1. Thus the rotor will stop at a point which will give a cross lane vehicle a favorable light without delay.
- 15 It is essential that means be provided whereby a late arriving vehicle on the cross road will not be trapped at the intersection if the signal is about to change against it. For this purpose a pair of opposed electro-magnets 28 and 29 are 20 assembled with the traffic signal and between the poles of the magnets there is mounted an armature 30 which is magnetically attracted by one or the other of the magnets to open or close a switch 31 in the circuit 27. The magnet 28 is connected in series with the vehicle operated switch 11 and in parallel with the motor circuit closing magnet 13, as shown at 32. The magnet 29 is connected in circuit 33 with a pair of switch contacts 34 which latter are in the path of a cam 30 35 on the program control rotor 20. The cam 35 is disposed to affect contact 34 at or near the end of the go period for the cross road, or at the beginning of the caution period that follows, so that a late arriving vehicle will command the right 35 of way regardless of its time of arrival. The magnet 28 should be more powerful than the magnet 29 in order to assure opening of the circuit 27 in the event that both magnets 28 and 29 are energized simultaneously.
- 40 When a late arriving vehicle that is, one arriving just as a change of signal is about to take place, passes over the vehicle operated switch 11 it will be seen that the circuit through the magnet 28 will be closed and the magnet thus energized attracts the armature 30 to open the switch 31 in the circuit 27 which controls the motor stopping electro-magnet 12. Consequently, when the advancing cam 25 closes the circuit 27 at the contacts 26 and magnet 12 cannot be energized to open the switch 15 and stop the motor since its circuit 27 is open at the switch 31, as shown in Figure 2. Thus the program control rotor must continue to another revolution during which time the late arriving vehicle may proceed safely across

the intersection under the protection of the green or go light of the cross road.

When the cam 35 subsequently closes the contacts 34 the magnet 29 will be energized to close the switch 31 which controls the circuit 27 so that 5 in the event of no more traffic appearing on the cross road, when the cam 25 next moves around into circuit closing position to close the circuit 27 at the contacts 26 the magnet 12 will be energized to open the switch 15 and break the motor 10 circuit to stop the motor.

From the above it will be apparent that a vehicle on a cross road approaching a main highway intersection will always command a go signal and yet grant the traffic on the main highway a 15 sufficient go interval to avoid unnecessary delay for traffic on the main highway.

From the above description it is thought that the construction and operation of the invention will be fully understood without further explanation.

What is claimed is:

In a traffic control system of the class described, a program control rotor, an electric motor for driving the rotor, a motor circuit which when 25 closed energizes the motor and when opened re-energizes the motor, a switch in the motor circuit, opposed electro-magnets one of which closes the switch and the other of which opens the switch, a vehicle operated switch connected in 30 circuit with the switch closing electro-magnet, switch means operated by the rotor and controlling the electro-magnet which opens the motor circuit switch to normally confine the rotor to a single revolution, and means for permitting the 35 rotor to continue through more than one revolution when the vehicle operated switch is actuated just as a change of signal is about to take place comprising a circuit, a switch in said circuit, opposed electro-magnets one of which closes the 40 switch and the other of which opens the switch, the electro-magnet which opens the switch being connected in series with the vehicle operated switch and being connected in parallel with the electro-magnet which closes the motor circuit 45 switch, switch contacts in said circuit, the other of the electromagnets being connected in series with the switch contacts, and a cam on the rotor for closing the switch contacts, coasting of the motor permitting the rotor to move sufficiently 50 to disengage said cam from said switch contacts to deenergize said electromagnet which opens said switch.

SAMUEL C. ROTH.

CERTIFICATE OF CORRECTION.

Patent No. 2,131,818.

October 4, 1938.

SAMUEL C. ROTH.

It is hereby certified that error appears in the printed specification of the above numbered patent requiring correction as follows: Page 1, first column, line 2, for "sgnal" read signal; page 2, first column, line 49, for "and magnet" read the magnet; same page, second column, line 26-27, for "re-energizes" read de-energizes; and that the said Letters Patent should be read with this correction therein that the same may conform to the record of the case in the Patent Office.

Signed and sealed this 24th day of January, A. D. 1939.

Henry Van Arsdale
